UNITED STATES PATENT OFFICE.

MARVIN H. JESTER, OF DENVER, COLORADO, ASSIGNOR TO THE M. H. JESTER INVESTMENT COMPANY, OF DENVER, COLORADO, A CORPORATION OF COLORADO.

METALLIC BOX-CLIP FOR PLASTER BOARDS OR BLOCKS FOR USE IN PARTITION-WALL AND CEILING CONSTRUCTION.

1,126,020.

Specification of Letters Patent. Patented Jan. 26, 1915.

Application filed June 23, 1913. Serial No. 775,322.

To all whom it may concern:

Be it known that I, MARVIN H. JESTER, a citizen of the United States of America, residing in the city and county of Denver and State of Colorado, have invented a new and useful Metallic Box-Clip for Plaster Boards or Blocks for Use in Partition-Wall and Ceiling Construction, of which the following is a specification.

My invention relates to an improved metallic box-shaped clip for use in partition wall and ceiling constructions, and the objects of my invention are: First, To provide a clip of this character which is used in connection with channel bar studding, said clips being arranged to be clamped to the studding so as to be held at the required position before the plaster boards are secured thereto. Second, To provide a clip having a channeled portion adapted to fit over the channel bar, and a separable yoke-shaped strip which engages the opposite side of the said channel bar, its ends being passed through an opening in the channeled portion of the clip and then bent to conform to the shape of said clip, whereby the clip is securely clamped upon the channel bar.

I attain these objects by the mechanism illustrated in the accompanying drawings, in which,

Figure 1 is a perspective view, showing a portion of a channel bar stud with the improved clip secured in position thereon. Fig. 2 is a similar view taken from the reverse side of Fig. 1. Fig. 3 is a perspective view of the clip detached from the channel bar stud, the attaching strip being omitted. Fig. 4 is a horizontal sectional view through a portion of a partition, showing the improved clip and the manner of securing plaster boards thereto. Fig. 5 is a horizontal sectional view similar to Fig. 4, but showing the ends of the securing strip bent to lie against the front side of the plaster boards instead of against their rear sides. Fig. 6 is an edge view of the securing strip. Fig. 7 is a front view of a portion of a partition illustrating the application of the improved clip. Fig. 8 is a horizontal sectional view, illustrating a slight modification of the clip to adapt the same for use in connection with thick plaster boards or blocks; and Fig. 9 is a side elevation of the form of clip shown in

Fig. 8, the securing strip being shown in dotted lines.

55

Similar letters of reference refer to similar parts throughout the several views.

My improved box-shaped clip is used in the construction of fire-proof plaster board or plaster block metal stud partitions, and 60 are called skeleton partitions or partition cores, and they are arranged and adapted to receive and support stucco and other plastering mortars and cements on their opposite sides, and when finished they make a stiff, 65 firm, rigid fire-proof partition of about two inches in thickness.

Referring to the drawings: The numeral 1 designates a metallic stud such as is used for studding in plaster board or plaster 70 block partition work, as is shown in Fig. 7. These studs are positioned vertically between the floors and ceilings of rooms and they are spaced a distance apart to receive and support between them the various sizes 75 of plaster boards manufactured for partitions, which are made in various sizes, the sizes most generally used for this class of partition being twenty-four, thirty and thirty-six inches apart.

80
The plaster boards vary in thickness from about a quarter of an inch to about three-eighths of an inch in thickness, and the plaster blocks are much thicker, varying from about five-eighths to an inch or over 85 in thickness.

In Figs. 4 and 5, fragmentary end portions of plaster boards 2, are shown connected to the stud 1 by my improved metallic clip, while in Fig. 8 the fragmentary 90 end portion of a plaster block is shown connected and supported to the stud 1 by my metallic clip. The stud may be of any suitable form of cross section. I preferably, however, use and have illustrated a channel 95 iron or bar form of metal stud, although I could use flat bar stud of iron or steel such as is illustrated in my Patent Number 1,001,146, issued to me August 22, 1911.

My improved clip is composed of two 100 parts 3 and 4, both parts of which are of yoke-shape and fit or fold around the channel stud from its opposite edges, and the part 4 folds around the channel bar within the part 3 and its free ends extend through 105 apertures 5, formed in the end 7 of the

yoke-shaped portion of the part 3. The part 3 is a yoke-shaped winged clip bent to have a closed end portion 7, fitting against one edge of the channel bar and side portions 8, arranged to fit loosely over the sides of the channel bar, and extending to even with the adjacent edge of the channel bar when the closed end of the clip 3 is bearing against the opposite edge of the channel bar, 10 and the sides 8, terminate in oppositely extending wings 9, which are arranged at substantially right angles to the sides 8, of the clip, which sides are preferably bent convergingly inward toward the channel bar 15 from the closed end of the clip, which makes the space between the two sides of the clip narrower at the open end of the clip than at the closed end portion of the clip, this angular arrangement of the sides of the 20 clip being especially provided to permit the sides to fit the narrowest channel bar made or to be sprung outwardly enough to fit over the widest channel bars made of the size used in this class of partition work, 25 which is generally of the size known as one inch channel bar, but the different makers of these small channel bars make them of slightly different widths, and the introverted angular arrangement of the sides is 30 made to permit the sides of this outside yoke portion of my clip to fit snugly the narrowest one inch channel made or to permit the sides to be sprung outwardly over the widest or thickest of the size of channel bars used 35 for this partition work.

The part 4 comprises a metal strip of the width of the opening 5 in the part 3. This strip is first bent in yoke form, as shown in Fig. 6, and is placed on the stud from the 40 opposite side to that upon which the clip 3 is placed, and its ends are passed through the opening 5. They are then bent down against the sides of the channeled or yoke shaped portion of the clip 3, and then at 45 right angles, so as to rest against the wings 9 of the clip. In this manner the clip is securely clamped upon the stud, and will not slip out of position, thus enabling a number of clips to be secured in position 50 upon the studs before the plaster boards are applied.

The studs are provided at intervals with apertures 10, and the sides 8 of the channeled portion of the clip are provided with 55 similar apertures 11, adapted to register with the apertures 10 when the clips are placed on the studs. The parallel sides of the strip 4 are also provided with apertures 12, which register with the apertures 10 and 60 11, and these apertures are such a distance from the wings of the clip that when the plaster boards 2 are placed against the said wings, their ends partially cover the said holes. These boards are placed against the 65 wings of the clips, or, more strictly speak-

ing, against the ends of the strips 4, with their ends abutting against the right angled sides of the strips, and the opposing ends of each two boards are clamped against the clip by driving an ordinary wire nail 14, 70 through the registering holes in the stud, the clip 3, and the strip 4. The part of the registering holes extending beyond the outer surface of the plaster boards provides an aperture of slightly less diameter than that 75 of the nail, so that when the nail is driven or pushed through the apertures, the contact of the nail with the marginal edges of the portions of the registering apertures beyond the outer surface of the plaster boards, 80 causes the nail to crowd or press against the boards, thereby clamping them to the clips. It is only necessary, however, to hold the boards in place by the nails, with a clamping pressure sufficient to hold the nails 85 in place, so that the use of a hammer for inserting the nails will be unnecessary.

After the boards have been secured, as shown in Fig. 7, they are given the usual rough and finishing coats of plaster, by 90 which the projecting portions of the studs with the clips and nails, are completely concealed, and the partition is then in a completed state.

This form of clip provides for securing 95 the plaster boards so as to form straight or unbroken joints along the lines of their opposing edges.

In Fig. 5, I have illustrated a slightly different arrangement from what is shown 100 in the preceding figures. In this arrangement, the same parts are employed, but the securing strip 15 in this case, after being bent over the sides 8 of the channeled portion of the clip 3, are bent at right angles 105 so as to lie against the outer faces of the plaster boards and not against their rear faces, as in Fig. 4. By this arrangement the boards are clamped between the wings of the clip and the ends of the strip 15, and the 110 securing nail bears against the ends of the strip. The apertures 16, in this strip are slightly out of line with those in the clip and stud, as shown, so that the outer part of its marginal edge will not be engaged by 115 the nail; otherwise the nail could not act to clamp the ends of the strip against the plaster boards.

In Figs. 8 and 9, I have illustrated a modification of the clip, in which the same 120 is arranged for securing plaster blocks, which are about twice the thickness of the plaster boards. In this arrangement, the yoked strip 4 is the same as shown in Figs. 1 to 4 inclusive, and Fig. 6, but in place of the plate 3, I substitute a plate 17, having a channeled portion 18, the end wall of which is provided with parallel slots 19, which release a strip 20, which is outwardly bowed or bulged, as shown. The plate 17 is 130

placed upon one side of the stud, and the yoked strip 4 is placed over the opposite side, its ends extending through the slots 19 of the channeled portion 18, after which 5 they are bent as in Fig. 4.

The plaster blocks are of the same thickness as the depth of the channeled portion 18 of the plate 17, so that when placed in position against the wings of the said plate, 10 their outer faces are flush with the end wall of the channeled portion 18, and by inserting a nail beneath the bowed strip 20, and against the faces of the blocks, the said blocks are clamped to the plate 17, as clearly 15 shown by Fig. 8.

Having described my invention, what I claim as new and desire to secure by Letters Patent, is:

1. In a clamping device for securing plaster boards to studding, the combination with a stud of a channeled clip-plate thereon having an opening in the channel thereof, a yoke-shaped strip which engages the stud from the opposite side, the ends of which 25 are passed through the opening in the channel and are bent to conform to the contour of the said clip-plate, and means for securing the plaster-boards against the ends of said clip-plate.

2. In a clip for plaster boards, as specified, the combination with a stud, of a clip-plate engaging one edge of the stud and having an aperture, a yoke engaging the other edge of the stud, the ends of which extend through the said aperture and are bent to engage the plate, and means for securing the plaster-boards against the ends of said clip-plate.

3. In a clip for plaster boards, as specified, the combination with a stud, of a channeled clip-plate which overlies one edge of said stud, an opening being formed in the end wall of the said channel, a yoke which overlies the other edge of said stud, the ends of which extend through the said aperture and are bent to engage the sides of the channel and lie parallel with the face of the plate, and means for securing the plaster-boards against the ends of said yoke.

4. In a clip for plaster boards as specified, the combination with a stud, of a clip-plate having a channel, the sides of which diverge from the plate, while an aperture is formed through its end wall, said channel portion being placed over one edge of the stud, a yoke-shaped strip which is passed over the opposite edge of the stud between the diverging sides of the channel, the ends of said strip extending through the opening in the channel and being bent over and against the sides of the same, and then parallel with the plate, and means for securing the plaster-boards against the ends of said strip.

5. A clamping device as specified, com-

prising a channeled clip-plate, the said channel having an aperture in its end wall, a yoke-shaped strip, the ends of which are passed through the said opening and bent around the sides of said channel, said yoke 76 and channel forming together a rectangular inclosure, and means for securing the plaster-boards against the ends of said strip.

6. In a clamping device for plaster boards as specified, the combination with a stud 75 of a U-shaped clip-plate having its channeled portion adapted to lie over said stud on one side, a yoke-shaped strip adapted to straddle the stud from the opposite side, the ends of which extend through an aperture 80 in said channel and are bent around the sides of the same, and means for securing the plaster-boards against the ends of said strip.

7. A securing-device for plaster-boards, 85 comprising a stud, a U-shaped plate having an apertured channel portion adapted to lie over the front edge of said stud and oppositely-extending wings, a yoke-shaped plate 90 adapted to lie over the rear edge of said stud having portions extending through the aperture of the channel portion of said U-shaped plate and bent to conform to the shape of the latter, and means for securing the plaster-boards against the portions of 95 said yoke-shaped plate overlying said wings.

8. A securing device for plaster-boards, comprising a stud, a clip-plate having a channeled portion engaging one edge of said stud, separable means engaging the opposite 100 edge of said stud and having portions extending through apertures in said channeled portion for securing said clip-plate to the stud, a keyway in the channeled portion of said clip-plate, and a key extending through 105 said keyway for securing the plaster-boards against the extended portions of said separable means.

9. A securing-device for plaster-boards, comprising a stud, a U-shaped clip-plate 110 having an apertured channeled portion adapted to lie over the front edge of said stud and oppositely-extending wings, a yoke-shaped plate adapted to lie over the rear edge of said stud having portions extending through the apertures of the channeled portion of said U-shaped plate, said extending portion being bent backward and outward to conform to the shape of said U-shaped plate, a keyway in the channeled portion of said clip-plate; and a key extending through said keyway for securing the plaster-boards against the ends of the extended portions of said yoke-shaped plate. 120

10. A securing device for plaster-boards, comprising a stud, a clip-plate having a channeled portion engaging one edge of said stud, separable means engaging the opposite edge of said stud and having portions extending through apertures in 125 said clip-plate.

4
channeled portion for securing said clip-plate to the stud, a raised bowed portion on the outside of said channeled portion of said clip-plate, and a key extending under
5 said raised portion for securing the plasterboards against the extended portions of said separable means.

In testimony whereof I affix my signature in presence of two witnesses.

MARVIN H. JESTER.
